UNITED STATES PATENT OFFICE.

HOWARD C. NOBLE, OF NEW BRITAIN, CONNECTICUT.

DESIGN FOR A BOOT-STRAP.

SPECIFICATION forming part of Design No. 13,985, dated June 19, 1883.

Application filed February 23, 1883. Term of patent 14 years.

To all whom it may concern:

Be it known that I, HOWARD C. NOBLE, a citizen of the United States, residing at New Britain, in the county of Hartford and State of Connecticut, have invented and produced a new and original Design for a Boot-strap, of which the following is a specification, reference being had to the accompanying drawings, forming part thereof.

10. Figure 1 is a side elevation of my newly-designed boot-strap. Fig. 2 is a front view of the same, and Figs. 3 and 4 are side elevations of the same with slight differences of adaptation.

I am aware that a prior patent shows a metallic boot-strap in substantially horseshoe form, with a transverse bar connecting the portions, which correspond with the heels of a horseshoe, said bar forming the bottom of the complete device, and the same is hereby disclaimed. Said design differs from mine in not defining the two complete ends of an oval figure, in having no vertical bars, in making the side bars of the shank slant toward each other, instead of being parallel, also in making the shank of a width fully equal to the widest part of the handle.

15. The leading feature of my design consists of an oval-shaped pull, when viewed in side elevation, connected to a rectangular shank having parallel sides, the width of which shank at its upper end is less than the width of the pull.

20. A designates the pull, whose contour in side view describes the upper side and the two ends of an oval-shaped figure, and therefore I term it an "oval-shaped pull." B designates the shank connected thereto, the same being composed of two parallel vertical bars, *a a*, and one cross-bar, *b*, at the bottom thereof.

25. The width of the shank B from outside to out-

side of the bars *a a* at their upper ends is less than that of the pull, whereby what may be termed the "rounded" ends or sides of the pull curve inward toward each other before they meet the upper ends of the vertical bars 45 *a a*. Although when attached to the boot the shank will be covered, its general form and position, by reason of its impression or stitching, &c., will be discernable. In Fig. 4 I have shown the shank B as having one of its bars *a* 50 *a* made longer than the other, whereby the angles formed at the junction of the shank and pull stand in the plane indicated by the broken line in said figure, instead of in the plane indicated by the broken line in Fig. 1. The 55 top of the pull in Fig. 4 also stands slanting in substantial conformity to the line before described from angle to angle. In Fig. 3 a slight downwardly-projecting point is formed upon the inside of the pull at the top, as shown. 60

I claim—

1. The design for a boot-strap herein shown and described, the same consisting of the oval-shaped pull A and the shank B, formed of the vertical parallel bars *a a* and cross-bar *b*, the 65 width of the shank at its extreme upper end being less than that of the pull, whereby a decided angle is formed upon each side of the strap at the junction of the shank and pull.

2. The design for a boot-strap herein shown and described, the same consisting of the oval-shaped pull A and the shank B, formed of the cross-bar *b* and vertical parallel bars *a a*, one of which bars projects upwardly higher than the other, as shown in Fig. 4. 70

HOWARD C. NOBLE.
